MATERIAL SEPARATOR AND ENERGY APPARATUS

Balázs Tarsoly, North Pelham, N. Y.

Application November 7, 1957, Serial No. 694,990

6 Claims. (Cl. 233—27)

This invention relates to the art of centrifugal separators for materials of different densities.

The invention is directed at providing a device adapted to separate gases, liquids, or finely divided solids. The device is adapted to separate mixtures of steam vapor and water, oils containing constituents of different densities or viscosities, dusts or powders of different sizes entrained in streams of air or liquid, etc.

A principal object of the invention is to provide a separator in which a vortex of great rotational velocity is obtained without use of baffles and impellers.

A further object is to provide a separator which has a dynamically balanced rotatable vortex chamber to increase the centrifugal forces upon the constituents to be separated.

A further object is to provide a separator including a turbine stator supporting a fluid driven rotor, with a vortex chamber for separating material contained in the rotor.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top plan view of an assembly of apparatus embodying the invention.

Fig. 2 is a perspective view of the apparatus of Fig. 1.

Fig. 3 is an elevational view partly in longitudinal section of a rotor employed in the separator.

Fig. 4 is a perspective view of the rotor.

Figs. 5 and 6 are top and perspective views respectively of inlet means for feeding material to be separated to the separator.

Fig. 7 is a perspective view of the stator of the separator with a portion broken away to show internal parts for supplying driving fluid to the rotor.

Fig. 8 is a cross-sectional view taken on lines 8—8 of Fig. 7.

Figs. 9 and 10 are top and perspective views respectively of outlet means for the separated material from the separator.

Fig. 11 is a sectional view of the rotor on an enlarged scale with paths of motion of the divided material indicated by dotted lines.

Fig. 12 is a plan view of a helically grooved ring employed in the rotor.

In Figs. 1 and 2, there is shown compressor 21 provided with an air inlet 22. The compressor serves to compress the air and deliver it at high pressure to the fluid divider shell 24. Valve 25 controls the air flow from the compressor via pipe 27. A gauge 28 indicates the pressure in the tank of the compressor. The compressor is driven by a motor 30 which is energized via wires 32 controlled by switch 31. The divider shell 24 is connected via pipes 33 and 34 to two further divider shells 35, 36 provided with pressure gauges 39 and 40.

2

Valves 41 and 42 control the flow of compressed air through pipes 33 and 34. Branch pipes 45 and 46 are connected from divider shell 36 to stator ring 48 of the separator. Branch pipes 50 and 51 are connected from divider shell 35 to another stator ring 49 of the separator. Stands 52 and 53 support the pipes between the divider shells 36, 36 and the stator rings.

The stator rings are mounted in retainers 55. The rings rest on a base plate 56. A rotor 60 is freely rotatable within the stator rings. The rotor has inlet tubes or pipes 61, 61^a at opposite ends for receiving the material to be separated in a chamber within the rotor. Inlet pipes 61 and 61^a terminate in shells 64 and 65. These shells have apertures 67^a in their inwardly facing sides 66 in which sides are mounted bearing rings 67. The ends of the inlet pipes are journaled to rotate in these bearings. Inlet feeder pipes 68 and 69 communicate through chambers in the shells 64, 65 with the open ends of pipes 61 and 61^a. These pipes are branches of the common feeder pipe 70 which is supplied with the material to be separated from a hopper 71. A valve 72 in pipe 70 controls the flow of the material through pipe 70.

Two pairs of pans 74, 76 and 74^a, 76^a are provided on each side of the stator rings. These pans are arranged to receive the separated material discharged from the rotor. Outlet pipes 80, 80^a are connected to pans 74, 74^a and outlet pipes 81, 81^a are connected to pans 74^a and 76^a. Pipes 80, 80^a join at the common outlet pipe 84. Pipes 81, 81^a join at the common outlet pipe 85.

The structure of the rotor 60 is best shown in Figs. 3, 4 and 11. The rotor includes an outer ring 87 formed with a succession of vanes 88 arranged as a chain of V's with central connecting walls 89. A generally cylindrical shell is formed by a pair of cylindrical shell members 78, 78^a having flanges 90 on the inner ends thereof. Bolts 91 secure the flanges of the two shell members together with the ring 87 disposed therebetween. The shell members 78, 78^a have inwardly tapered ends 78^b.

Tubes or pipes 92 and 92^a are concentrically disposed around pipes 61 and 61^a. Radially disposed ribs 93 secure the tubes 92, 92^a within the shell members. One end of each tube 92, 92^a extends out of the respective shell member and has a flange 94 disposed thereon. These flanges are slightly spaced from the open ends of the tapered portions 78^b of the shell members. Spaced from flanges 94 are other flanges 95. These flanges have smaller diameters than flanges 94. Flanges 95 are spaced from the open ends of tubes 92 and 92^a. Rings 96 and 96^a having helical grooves 97 therein are mounted on the inner ends of tubes 61 and 61^a and extend peripherally to shell members 78, 78^a. The rings are secured by welding or otherwise to the shell members and to the tubes 61, 61^a. Grooves 97 form helical passages with the inner walls of the shell members. A central chamber 98 is thus formed within the rotor. This chamber communicates via the helical passages with the annular openings between tubes 92, 92^a and shell members 78, 78^a. The chamber 98 also communicates with the annular openings between tubes 61, 61^a and tubes 92, 92^a.

In Fig. 11 the showing of rings 96 and 96^a is omitted in order to show the helical paths P of material flowing from chamber 98 to the two outlets at each end of the rotor. The path of flow of material into the rotor is shown by dotted lines A and the paths of the separated material is shown by dotted lines B and C respectively. Chamber 98 serves as a mixing and comminuting chamber for the material entering via pipes 61 and 61^a.

In Figs. 1, 2, 5 and 6 are shown the arrangement of the inlet pipes 68 and 69 which are connected between feeder pipe 70 and the shells 64 and 65. The ends of

pipes 61, 61^a fit into apertures 67^a and are rotatable therein on bearings 67 shown in Fig. 2. A pressure gauge 73 may be provided in pipe 70 for indicating the pressure of material flowing therethrough into pipes 68, 69.

In Figs. 7 and 8 are shown the details of the stator rings 48 and 49. These rings are endless tubes. Pipes 45 and 46 are connected at diametrically opposed points to ring 48 and pipes 50, 51 are connected similarly to ring 49. The rings have each a plurality of nipples 47 opening in their lower sides. The rings are secured to an outer band 54 which has a plurality of spaced passages 57 communicating with nipples 47 in the rings 48, 49. Another band 58 provided with pairs of diagonally extending passages 59, 59^a is disposed inside band 54. Band 58 is prevented from moving with respect to band 54 by loosely contacting serrated plates 62 and 62^a respectively mounted on the sides of band 58 and rings 48, 49. A handle 63 has laterally disposed bars 63^a connected to both plates 62 on band 58. The teeth of plates 62, 62^a are rather loosely engaged so that the inner band 58 can be moved slightly circumferentially with respect to band 54. At one end of the movement of band 58 passages 57 communicate with passages 59 and at the other end of movement of the inner band passages 57 communicate with passages 59^a. Rings 48 and 49 are prevented from rotating by their mounting in retainers 55.

Rotor 60 is rotatably mounted in the band 58. When the handle bars 63^a are vertical, passages 57 and 59 are in communication, so that streams of air at high pressure emitted from passages 59 impinge on vanes 88 and cause the rotor to rotate at high speed. When it is desired to stop the rotor, the handle 63 is moved to cause passages 57 to communicate with the passages 59^a. The air streams will now be directed obliquely at the vanes 88 in directions which will oppose the rotation of the rotor so that the rotor is gradually brought to a stop. The device is thus provided with an air braking means. The device uses compressed air to rotate the rotor and to brake the rotor.

In Figs. 1, 2, 9 and 10 are shown the pans 74, 74^a which receive the separated material from rotor openings adjacent flanges 94 of the rotor. These pans have cavities which communicate with outlet 84 via pipes 80, 80^a. On its inner side 74' each of these pans has an opening 82 which is large enough to pass the flanges 94 and 95 of the rotor. The outer side 83 of each of pans 74, and 74^a has an opening 86 best shown in Fig. 2, which opening is just large enough to pass the flange 95 at each end of the rotor. Flanges 94 are rotatably disposed in the pans 74, 74^a and close the openings 86. The outer ends of tubes 92 and 92^a extend through openings 86 and terminate in pans 76 and 76^a. These pans are connected via pipes 81, 81^a to outlet pipe 85. The outer sides 76' of pans 76, 76^a have openings 79 through which pass the ends of pipes 61 and 61^a respectively. Flanges 95 are disposed in pans 76, 76^a and are located adjacent sides 76'. Openings 77 in the inner sides of pans 76, 76^a are just large enough to pass the flanges 95 of the rotor.

By the arrangement of the pans and their associated outlet pipes, all materials separated in the rotor pass in parallel streams to pipes 80, 80^a and 81, 81^a.

In operation of the apparatus, the rotor will be driven by compressed air provided by compressor 21 and fed via the stator rings. Material to be separated such as finely divided solids in a liquid carrier will pass from container 71 into the chamber 98 in the rotor. The material passes in two opposed streams into the chamber where a turbulent condition is established. The rapid rotation of the rotor imparts a rotating swirling motion to the mixing streams which divide into equal parts passing through the two helical passages 97 in the two rings 96 and 96^a best shown in Figs. 3 and 12. Due to the different densities and masses of the substances in the rotating streams, particles of greater density will pass out of the radially outer spaces between the shell members 78, 78^a and tubes

92, 92^a into pans 74, 74^a. Particles of lesser density will pass out of the radially inner spaces between tubes 61, 61^a and tubes 92, 92^a into pans 76, 76^a.

Instead of a hopper 71, there may be provided a closed container supplying a mixture of gases, or liquids under pressure to the rotor for separation thereby.

The separated materials passing through outlet pipes 84 and 85 may be collected in suitable containers. If desired, the rather high kinetic energy imparted to the streams of materials in the several outlet pipes may be fed to suitable turbines or other engines to perform useful work.

It will be noted that the entire assembly of the rotor 60 has a balanced symmetrical structure. This permits the separator to operate at high speeds of the order of 10,000 or more R. P. M. The high speed of rotation of the mixture of oppositely directed streams in chamber 58 causes a very fine comminution of the streams to take place so that the streams passing through rings 96, 96^a 20 are really fine sprays of minute droplets rather than heavy streams of solidly flowing material.

If the apparatus be used primarily for performance of useful work by the several high pressure streams issuing from outlets 84 and 85, the apparatus may be regarded 25 as an energy converter, in which the latent energy in the compressed air which drives the rotor is converted to kinetic energy in the streams of fluid in the several outlets.

While I have illustrated and described the preferred embodiment of my invention, it is to be understood that 30 I do not limit myself to the precise construction herein disclosed and that various changes and modifications may be made within the scope of the invention as defined in the appended claims.

Having thus described my invention, what I claim as 35 new, and desire to secure by United States Letters Patent is:

1. A material separation apparatus, comprising a stator, means for supplying compressed gas to the stator, a rotor having a plurality of vanes rotatably mounted in the 40 stator and positioned to receive said compressed gas from the stator, said rotor having a generally cylindrically walled chamber, mechanical means mounted on the stator and arranged to direct said gas in one direction on the vanes to rotate the rotor and to direct said gas in another direction on the rotating rotor to stop rotation thereof, tubular inlets supplying material to be separated into streams of two different densities connected to opposite ends of the rotor and opening into said chamber, said rotor having two outlets at each end, and a pair of spaced 45 axially aligned rings respectively mounted between an inner end of each tubular inlet and the wall of said chamber, each ring having a helical groove therein to provide a helical passage between an inlet and an outlet of the rotor, one outlet at each end of the rotor being adapted 50 to emit streams of material having one density and the other outlet at each end of the rotor being adapted to emit streams of material having a different density.

2. A material separation apparatus, comprising a stator including a pair of endless hollow rings, a first cylindrical band supporting said rings, retainer means maintaining the rings in vertical stationary positions side by side on said band; another band movably disposed within the first band, manually operable means operatively connecting said inner band to said rings for controlling 60 movement of the inner band, said rings having spaced openings communicating with radial passages in the first band, said inner band having obliquely disposed pairs of passages, the passages in each of said pairs alternatively communicating with the radial passages at opposite extremes of movement of said inner band, a rotor rotatably mounted in said inner band, said rotor including an outer ring formed with a chain of V-shaped vanes, a chamber formed in said outer ring, a pair of cylindrical shell members secured in axial alignment to said outer ring, a 65 first pair of tubes extending into said shell members from

opposite ends thereof, a second pair of tubes respectively concentrically surrounding the first tubes and disposed between the first tubes and the shell members, a second pair of rings each having a helical groove therein respectively mounted between the inner end of each of the first tubes and one of the shell members, each of the first and second tubes having a radially extending flange near the outer end thereof and disposed outside the shell members, a container for material to be separated into constituents of greater and lesser density connected to the outer ends of the first tubes, a first pair of pans, said first tubes extending axially through said pans with the second tubes terminating in the pans, and a second pair of pans, said second tubes extending axially through the second pair of pans with the shell members terminating in the second pans.

3. A material separation apparatus, comprising a stator including a pair of endless hollow rings, a first cylindrical band supporting said rings, retainer means maintaining the rings in vertical stationary positions side by side on said band, another band movably disposed within the first band, manually operable means operatively connecting said inner band to said rings for controlling movement of the inner band, said rings having spaced openings communicating with radial passages in the first band, said inner band having obliquely disposed pairs of passages, the passages in each of said pairs alternatively communicating with the radial passages at opposite extremes of movement of said inner band, a rotor rotatably mounted in said inner band, said rotor including an outer ring formed with a chain of V-shaped vanes, a chamber formed in said outer ring, a pair of cylindrical shell members secured in axial alignment to said outer ring, a first pair of tubes extending into said shell members from opposite ends thereof, a second pair of tubes respectively concentrically surrounding the first tubes and disposed between the first tubes and the shell members, a second pair of rings each having a helical groove therein respectively mounted between the inner end of each of the first tubes and one of the shell members, each of the first and second tubes having a radially extending flange near the outer end thereof and disposed outside the shell members, a container for material to be separated into constituents of greater and lesser density, a first pair of branch pipes extending from the container to a pair of shell bearing members, the outer ends of the first tubes being rotatably disposed in the shell bearing members and communicating with said branch pipes, a first pair of pans, said first tubes extending axially through said pans with the flanges thereon nested in the pans, a second pair of branch pipes connected to the pans and communicating with said chamber via annular spaces between the first and second tubes, said second pair of branch pipes terminating in a first common outlet pipe, a third pair of branch pipes, a second pair of pans, said second tubes extending axially through the second pair of pans, a fourth pair of branch pipes connected to one of the hollow rings, a fifth pair of branch pipes connected to the other hollow ring, and means to supply compressed gas to the fifth and sixth pairs of branch pipes to drive the rotor, whereby rotation of the rotor causes material delivered to the rotor from the container to be separated into four finely comminuted streams of material of two different densities, each two streams having the same density being delivered to the same outlet pipe.

4. A material separation apparatus, comprising a stator including a pair of endless hollow rings, a first cylindrical band supporting said rings, retainer means maintaining the rings in vertical stationary positions side by side on said band, another band movably disposed within the first band, manually operable means operatively connecting said inner band to said rings for controlling movement of the inner band, said rings having spaced openings communicating with radial passages in the first band, said inner band having obliquely disposed pairs of passages, the passages in each of said pairs alternatively communicating with the radial passages at opposite extremes of movement of said inner band, a rotor rotatably mounted in said inner band, said rotor including an outer ring formed with a chain of V-shaped vanes, a chamber formed in said outer ring, a pair of cylindrical shell members secured in axial alignment to said outer ring, a first pair of tubes extending into said shell members from opposite ends thereof, a second pair of tubes respectively concentrically surrounding the first tubes and disposed between the first tubes and the shell members, a second pair of rings each having a helical groove therein respectively mounted between the inner end of each of the first tubes and one of the shell members, each of the first and second tubes having a radially extending flange near the outer end thereof and disposed outside the shell members, a container for material to be separated into constituents of greater and lesser density, a first pair of branch pipes extending from the container to a pair of shell bearing members, the outer ends of the first tubes being rotatably disposed in the shell bearing members and communicating with said branch pipes, a first pair of pans, said first tubes extending axially through said pans with the flanges thereon nested in the pans, a second pair of branch pipes connected to the pans and communicating with said chamber via annular spaces between the second tubes and the shell members, and means to deliver gas under pressure to the rotor for driving the rotor and causing said material to be separated.

5. A material separation apparatus, comprising a stator including a pair of endless hollow rings, a first cylindrical band supporting said rings, retainer means maintaining the rings in vertical stationary positions side by side on said band, another band movably disposed within the first band, manually operable means operatively connecting said inner band to said rings for controlling movement of the inner band, said rings having spaced openings communicating with radial passages in the first band, said inner band having obliquely disposed pairs of passages, the passages in each of said pairs alternatively communicating with the radial passages at opposite extremes of movement of said inner band, a rotor rotatably mounted in said inner band, said rotor including an outer ring formed with a chain of V-shaped vanes, a chamber formed in said outer ring, a pair of cylindrical shell members secured in axial alignment to said outer ring, a first pair of tubes extending into said shell members from opposite ends thereof, a second pair of tubes respectively concentrically surrounding the first tubes and disposed between the first tubes and the shell members, a second pair of rings each having a helical groove therein respectively mounted between the inner end of each of the first tubes and one of the shell members, each of the first and second tubes having a radially extending flange near the outer end thereof and disposed outside the shell members, a container for material to be separated into constituents of greater and lesser density, a first pair of branch pipes extending from the container to a pair of shell bearing members, the outer ends of the first tubes being rotatably disposed in the shell bearing members and communicating with said branch pipes, a first pair of pans, said first tubes extending axially through said pans with the flanges thereon nested in the pans, a second pair of branch pipes connected to the pans and communicating with said chamber via said second pair of pans with the shell members terminating in the second pans.

ond rings and annular spaces between the first and second tubes, said second pair of branch pipes terminating in a first common outlet pipe, a second pair of pans, said second tubes extending axially through the second pair of pans with the flanges on the second tubes nestled in the second pans, a third pair of branch pipes connected between another common outlet pipe and the second pans and communicating with said chamber via said second rings and annular spaces between the second tubes and the shell members, a fourth pair of branch pipes connected to one of the hollow rings, a fifth pair of branch pipes connected to the other hollow ring, and means to supply compressed gas to the fifth and sixth pairs of branch pipes respectively, whereby air under pressure is delivered to the stator and caused to impinge upon the vanes of the rotor to rotate the rotor at high speed, and whereby rotation of the rotor causes material delivered from said container to said chamber via said first and second pair of branch pipes to be separated into a pair of finely comminuted streams of material separately emitted from each end of the rotor into the first and second pans respectively, so that the separate streams are delivered to the respective outlet pipes in two merged streams of different density material.

6. A material separation apparatus, comprising a stator including a pair of endless hollow rings, a first cylindrical band supporting said rings, retainer means maintaining the rings in vertical stationary positions side by side on said band, another band movably disposed within the first band, manually operable means operatively connecting said inner band to said rings for controlling movement of the inner band, said rings having spaced openings communicating with radial passages in the first band, said inner band having obliquely disposed pairs of passages, the passages in each of said pairs alternatively communicating with the radial passages at opposite extremes of movement of said inner band, a rotor rotatably mounted in said inner band, said rotor including an outer ring formed with a chain of V-shaped vanes, a chamber formed in said outer ring, a pair of cylindrical shell members secured in axial alignment to said outer ring, a first pair of tubes extending into said shell members from opposite ends thereof, a second pair of tubes respectively concentrically surrounding the first tubes and disposed between the first tubes and the shell members, a second pair of rings each having a helical groove

therein respectively mounted between the inner end of each of the first tubes and one of the shell members, each of the first and second tubes having a radially extending flange near the outer end thereof and disposed outside the shell members, a container for material to be separated into constituents of greater and lesser density, a first pair of branch pipes extending from the container to a pair of shell bearing members, the outer ends of the first tubes being rotatably disposed in the shell bearing members and communicating with said first branch pipes, a first pair of pans, said first tubes extending axially through said pans with the flanges thereon nestled in the pans, a second pair of branch pipes connected to the pans and communicating with said chamber via said second rings and annular spaces between the first and second tubes, said second pair of branch pipes terminating in a first common outlet pipe, a second pair of pans, said second tubes extending axially through the second pair of pans with the flanges on the second tubes nestled in the second pans, a third pair of branch pipes connected between another common outlet pipe and the second pans and communicating with said chamber via said second rings and annular spaces between the second tubes and the shell members, a fourth pair of branch pipes connected to one of the hollow rings, a fifth pair of branch pipes connected to the other hollow ring, an air compressor, a gas divider shell, a pipe connected between the compressor and divider shell, a sixth pair of branch pipes connected between the divider shell and the fifth and sixth pairs of branch pipes respectively, whereby air under pressure is delivered to the stator and caused to impinge upon the vanes of the rotor to rotate the rotor at high speed, and whereby rotation of the rotor causes material delivered from said container to said chamber via said first and second pair of branch pipes to be separated into a pair of finely comminuted streams of material separately emitted from each end of the rotor into the first and second pans respectively, so that the separate streams are delivered to the respective outlet pipes in two merged streams of different density material.
